Inventor

Attorney

UNITED STATES PATENT OFFICE

JULIUS LASTOWSKI STONE, OF PHILADELPHIA, PENNSYLVANIA

FOLDING UMBRELLA

Application filed March 18, 1931. Serial No. 523,398.

This invention relates to umbrellas, parasols and the like, while it has more particular reference to that type of such articles which is adapted for folding into a minimum over-all-length so as to enable compact carriage when not in use.

The primary object of my invention is to provide an umbrella of the kind referred to which can be triple-folded into an exceedingly compact form for storage in a waterproof case designed for convenient carriage in the coat pocket or for suspension on the person.

Another object is to provide an umbrella of the type specified which automatically collapses and folds inwardly towards the point or tip; or one which, when collapsed, bunches up somewhat into cylindrical formation between the handle or knob end and the tip to compact form for easy insertion into a waterproof tube or closure case.

A further object of this invention is to provide a foldable umbrella characterized in that the outer or lower rib sections ordinarily coextensive with and serving as extensions of the upper main ribs, when the umbrella is expanded, have capacity to automatically flex or fold over towards said main ribs and thereby effectively combat the prevailing objections arising when sudden gusts of wind tend to turn or wrench the umbrella inside-out.

A still further object is the provision of a foldable umbrella that is simple in construction, comparatively cheap to manufacture, is not easily deranged, and which automatically triple-folds and simultaneously telescopes into approximately one-third of its extended dimension when collapsed.

Other and further objects not at this time appearing will be hereinafter referred to; while the invention consists of the novel construction herein described and finally claimed.

The nature, characteristic features and scope of my improvements will be more fully understood from the following description taken in connection with the accompanying drawings, wherein like parts are designated

by the same reference characters throughout the several views.

Fig. 1 is a broken sectional elevation of a practical embodiment of my foldable umbrella in the extended or open position. 55

Fig. 2 is a similar sectional view of the umbrella in the folded-telescopic position.

Fig. 3 is a broken elevation of the umbrella staff or stick.

Fig. 4 is a sectional detail, on a larger 60 scale, taken as indicated by the arrows 4—4 on Fig. 1.

Fig. 5 is a similar view taken on the plane designated 5—5 on Fig. 1.

Fig. 6 is a corresponding sectional view 65 taken on the plane 6—6 of Fig. 1.

Fig. 7 is a similar view taken as indicated by the arrows 7—7 on Fig. 1.

Fig. 8 is a sectional view, on an exaggerated scale, of the upper and lower rib portions, the stay or brace, and the associated actuating means, in expanded relation. 70

Fig. 9 is a section on the plane designated 9—9 in Fig. 8.

Fig. 10 is a section on the plane designated 75 10—10 in Fig. 8.

Fig. 11 is a section on the plane designated 11—11 in Fig. 8.

Fig. 12 is a perspective view of an actuating element hereinafter fully explained. 80

Fig. 13 is a view similar to Fig. 8 but showing how the lower or outer rib portion may automatically fold over under the influence of a sudden gust of wind.

Fig. 14 is a view showing the parts illustrated by Fig. 8 in collapsed relation; and, 85

Fig. 15 is a view of the umbrella in collapsed state with the associated container designed by me for purposes storing said umbrella when not in use, or after use, and 90 in wet condition.

Referring more in detail to the drawings it will be observed that the umbrella staff or stick comprises three relatively telescopic sections 1, 2 and 3; the sections 1 and 2 being 95 tubular, and the section 3, a rod. The staff or stick section 1 is provided, as best understood from Figs. 1, 2 and 7, proximate the lower end with radial indentations 4 serviceable firstly as sockets for the clamping attach- 100

ment, as by means of a screw 5, of a flattened knob or handle 6; and secondly as an abutment for the lower end of the rod section 3 when the umbrella is closed, as shown in Fig. 2. The section 1 is also provided with opposed longitudinal slots 7, extending the major portion of its length, that serve as guides for diametrically disposed pin 8 carried by a slideable runner or sleeve 9, and piercing the lower end of the rod section 3.

The tubular staff or stick section 2 is longitudinally split at diametrically opposing points of its lower end to provide slots 10 for coaction with the pin 8 aforesaid, while the released tongues of metal are retroverted or rolled over to form lugs 11 for engagement in the longitudinal slots 7, of the stick section 1. Also, at the upper end, the tube section 2 is longitudinally split to provide a series of circumferential tongues which are retroverted or turned over to provide bearing ears 12 for a conventional wire ring 13 affording pivotal connection for the inner ends of the umbrella brace or stay members 14, which it is to be noted are arcuately shaped at 15, for a purpose later on explained.

The rod section 3 of the staff or stick section is fitted at its outer or upper end with a rigidly-secured conventional annulus 16 and pivot ring 17 for the adjoining ends of upper rib portions 18, while 19 designates the usual covering, and 20 a small knob conveniently screw-threaded onto the reduced tip end 21 of said section 3; or such knob may be otherwise rigidly secured in place. Attention is also directed to the fact, at this juncture, that the upper rib portions 18 are also curved at 22, similar to the brace or stay ends 15, and likewise for a purpose hereinafter explained.

Referring again to the runner or sleeve 9, the same is fitted about its upper part with a conventional ring 23 for pivotal connection of strut or stretcher members 24 having slotted connection 25 with pins 26 in the brace or stay members 14; said slotted connection accommodating inward folding or collapse of the stays 14 and rib sections 18 in a manner obvious from Fig. 2, while the curved portions 15, 22 respectively thereof materially aid such compact folding as well as serving an additional purpose hereinafter explained.

Referring again to the brace or stay member 14 it will be seen, on reference to Figs. 8, 13 and 14, the same is provided, at the outer end, with a relatively-slidable saddle-like member 27 of U-shape cross section, terminating in an ear 28, for pivotal connection to the outer end of the rib section 18 by means of a pin 29. Each saddle portion 27, or the interconnected end of the brace or stay member 14, is provided with transverse rack teeth, conveniently although not essentially, in the form of pins 30, into which mesh the teeth of a pinion 31, likewise journaled in said saddle

portion by means of a shouldered pin 32. This pinion has connected thereto a link 33, the purpose whereof will be later on explained.

Pivotedly connected by a pin 18' to the outer end of the rib section 18 is a stirrup clip 35 to which the lower rib 36 is similarly attached by a pin 37; while said stirrup clip is reinforced by a stiffener 38 conveniently riveted in place, as indicated at 39, whereby the paralleling portions 40 of such stirrup clip are maintained in rigid relation.

Fulcrumed by an arbor 41 between the clip portions 40 is a triangular actuator 42, to the one angular point of which the link 33 is pivoted at 43; while a curvilinear link 44 is pivoted at 45 to the other angular point. This curvilinear link 44 is fulcrumed at 46 to the lower rib 36.

For convenience in carrying my improved umbrella in compactly folded form I have provided a water proof case 47, Fig. 15, preferably of moisture impervious fiber or bakelite, the same being fitted with a removable cap 48, and opposed bail-like loops 49, through which a cord or strap 50 of suitable length is passed, and whereby the device may be slung from the shoulder when not in use, in an obvious manner; or, such strap or cord may be removed and the case 47 carried in the pocket, or suspended by one of the loops 49 in the tonneau of an automobile, or similar vehicle.

Having described the structural components of my improved folding umbrella the operation thereof may be briefly set forth as follows:—

Assuming the several parts are in the folded up or relatively collapsed position best appreciated from Fig. 2, the user grips the runner or sleeve 9, or the tip knob 20, between the fingers of one hand and the handle 6 in the other, and gives the latter a slight turn counter-clockwise to disengage opposed outwardly-divergent locking notches 51, best seen in Fig. 3, at the lower ends of the stick section 1 longitudinal slots 7, from locking engagement with the pin 8. The stick section 1 is next drawn outwards until the upper closed ends of the slots 7 engage the lugs 11 at the lower part of the intermediate staff or stick tubular section 2, whereupon expansion of the upper ribs 18 is initiated and, as such expansion advances the slideable saddle members are extended relative to the braces or stays 14 with concurrent rotation of the pinions 31, while the struts or stretcher members 24 are expanded angularly outwards until the lower ends of their slots 25 abut the stay pins 26 and arrest further opening of the umbrella. Simultaneously with the rotation of the pinions 31 just described the rib sections 36 will be moved from the position shown in Figs. 2 and 14, to that illustrated in Figs. 1 and 8, with concurrent swinging of

the actuators 42 on their axes or pintles 41. Incident to swinging of the actuators 42, the curvilinear links 44 are inwardly retracted and thereby effecting outfolding of the 5 lower rib portions 36 from the position of Figs. 2 and 14, into alignment with the upper portions 18, as readily understandable from Figs. 1 and 8. The user, thereupon gives the handle 6 a slight clockwise turn 10 which moves the pin 8 into locking engagement with notches 52 at the upper end of the stick section 1, said notches being reversely inclined to the notches 51 hereinabove referred to, whereby the umbrella is securely 15 held in the full open state with the covering 19 properly stretched.

Obviously in closing the umbrella the sequence of movements is reversed, and when closed after use it will be readily seen that 20 it can be compactly closed in the case 47 without accumulated moisture being exposed to cause annoyance and damage incident to transportation or placement of said case in the pocket or on the cushions of an automobile.

Although I have shown and described but one form of my invention for purposes of practical illustration, it is to be understood that it is susceptible of various changes and 30 modifications in the minor details of construction, without departing from the scope of the following claims.

Having thus described my invention what I claim is:—

35 1. A folding umbrella comprising a stick of relatively telescopic sections, a series of ribs radiating from and operatively connected to the innermost stick section, each rib comprising an upper and a lower pivotally connected portions, a corresponding series of stays operatively connected to an intermediate stick section, each stay having a relatively 40 slidible element pivotally joined to the upper rib portion, means coordinating the rib portions for movement from or into folded relation to and from mutual alignment respectively, mechanism actuatable incident to movement between the stay and its slidible element to operate the rib coordinating means, 45 and a runner on the outermost stick section with stretchers having a lost motion connection with the stays to effect opening and closing of the umbrella.

50 2. A folding umbrella comprising a stick of relatively telescopic sections, a series of ribs radiating from and operatively connected to the innermost stick section, each rib comprising an upper and a lower member pivotally joined by a stirrup clip, a like series 55 of stays operatively connected to an intermediate stick section by a pivot ring held in place by bearing ears retroverted out of said section, a relatively slidible element at the outer end of each stay operatively connected 60 to the associated upper rib member, means

coordinating the rib members for movement from or into folded relation to and from mutual alignment respectively, mechanism actuatable incident to movement between the stay and slidible element to operate the rib 70 coordinating means, and a runner on the outermost stick section with stretchers having a pin and slot lost motion connection with the stays to effect opening and closing of the umbrella. 75

3. A folding umbrella comprising a stick of relatively telescopic sections, a series of ribs radiating from and operatively connected to the innermost stick section, each rib comprising an upper and a lower member pivotally joined by a stirrup clip, a like series of stays operatively connected to an intermediate stick section by a pivot ring held in place by bearing ears retroverted out of said section, a relatively slidible element at the outer end of each stay operatively connected to the upper rib member, means coordinating the rib members for movement from or into folded relation to and from mutual alignment respectively, mechanism actuatable incident to movement between the stay and slidible element to operate the rib coordinating means, a runner on the outermost stick section with stretchers having a pin and slot lost motion connection with the stays to effect opening and closing of the umbrella, and means for locking said umbrella in either the open or closed state by a slight turn of the outermost stick section. 95

4. A folding umbrella comprising a stick consisting of an outer and an intermediate tubular section with an inner rod relatively telescopic within said sections, a series of ribs radiating from and operatively connected to the tip of the rod section, each rib including an upper and a lower component joined by a stirrup clip, a like series of stays operatively connected to retroversions integral with the intermediate tubular section upper end, a relatively slidible saddle member at the outer end of each stay having pivot connection to an associated upper rib component, means coordinating the rib components for movement from or into folded relation to and from mutual alignment respectively, mechanism actuatable incident to movement between the stay and slidible saddle member to operate the rib co-ordinating means, a runner slidible along the outer tubular section having a like series of struts with pin and slot connection to the stays to effect opening and closing of the umbrella, and means to lock the umbrella in the open or closed state by a slight turn of said outer tube section. 110

5. A folding umbrella comprising a stick consisting of an outer and an intermediate tubular section with an inner rod relatively telescopic within said sections, a series of ribs ra- 130

diating from and operatively connected to the tip of the rod section, each rib including an upper and a lower component joined by a stirrup clip, a like series of stays operatively connected to retroversions integral with the intermediate tubular section upper end, a relatively slideable saddle member at the outer end of each stay having pivot connection to an associated upper rib component, a pinion journaled in the saddle member rotatable by rack means in the coactive stay end, means co-ordinating said pinion with the lower rib component to effect its movement from or into folded relation to and from mutual alignment with the upper rib component, a runner slideable along the outer tubular section having a like series of struts with pin and slot connection to the stays to effect opening and closing of the umbrella, and means to lock the umbrella in the open or closed state by a slight turn of said outer tube section.

6. A folding umbrella comprising a stick consisting of an outer and an intermediate tubular section with an inner rod relatively telescopic within said sections, a series of ribs radiating from and operatively connected to the tip of the rod section, each rib including an upper and a lower component joined by a stirrup clip, a like series of stays operatively connected to retroversions integral with the intermediate tubular section upper end, a relatively slideable saddle member at the outer end of each stay having pivot connection to an associated upper rib component, a pinion journaled in the saddle member rotatable by rack means in the coactive stay end, a triangular rocker pivoted in the stirrup clip with link connections to the lower rib component and the pinion aforesaid to effect folding and unfolding of said component with respect to the upper rib component, a runner slideable along the outer tubular section having a like series of struts with pin and slot connection to the stays to effect opening and closing of the umbrella, and means to lock the umbrella in the open or closed state by a slight turn of said outer tube section.

7. A folding umbrella comprising a stick consisting of an outer and intermediate tubular section with an inner rod relatively telescopic within said sections, a series of ribs radiating from and operatively connected to the tip of the rod section, each rib including an upper and a lower component joined by a stirrup clip, a like series of stays operatively connected to retroversions integral with the intermediate tubular section upper end, a relatively slideable saddle member at the outer end of each stay having pivot connection to an associated upper rib component, a pinion journaled in the saddle member rotatable by rack means in the coactive stay end, a triangular rocker pivoted in the stirrup clip with link connections to the lower rib component

and the pinion aforesaid to effect folding and unfolding of said component with respect to the upper rib component, opposed slots longitudinally of the outer tube section with which retroversions at the lower end of the intermediate tube engage, a runner slideable along the outer tubular section having a like series of struts with pin and slot connection to the stays to effect opening and closing of the umbrella, and means to lock the umbrella in the open or closed state by a slight turn of said outer tube section.

8. A folding umbrella comprising a stick consisting of an outer and an intermediate tubular section with an inner rod relatively telescopic within said sections, a series of ribs radiating from and operatively connected to the tip of the rod section, each rib including an upper and a lower component joined by a stirrup clip, a like series of stays operatively connected to retroversions integral with the intermediate tubular section upper end, a relatively slideable saddle member at the outer end of each stay having pivot connection to an associated upper rib component, a pinion journaled in the saddle member rotatable by rack means in the coactive stay end, a triangular rocker pivoted in the stirrup clip with link connections to the lower rib component and the pinion aforesaid to effect folding and unfolding of said component with respect to the upper rib component, opposed slots longitudinally of the outer tube section with which retroversions at the lower end of the intermediate tube engage, a runner having rigid diametric pin connection to the lower end of the inner rod and slideable along the outer tubular section, a like series of struts operatively pivoted to said runner and having pin and slot connection with the stays to effect opening and closing of the umbrella, and means to lock the umbrella in the open or closed state by a slight turn of the outer tube section.

9. A folding umbrella comprising a stick consisting of an outer and an intermediate tubular section with an inner rod relatively telescopic within said sections, a series of ribs radiating from and operatively connected to the tip of the rod section, each rib including an upper and a lower component joined by a stirrup clip, a like series of stays operatively connected to retroversions integral with the intermediate tubular section upper end, a relatively slideable saddle member at the outer end of each stay having pivot connection to an associated upper rib component, a pinion journaled in the saddle member rotatable by rack means in the coactive stay end, a triangular rocker pivoted in the stirrup clip with link connections to the lower rib component and the pinion aforesaid to effect folding and unfolding of said component with respect to the upper rib component, opposed slots longitudinally of the outer tube section with which re-

troversions at the lower end of the intermediate tube engage, a runner having rigid diametric pin connection to the lower end of the inner rod and slideable along the outer tubular section, a like series of struts operatively pivoted to said runner and having pin and slot connection with the stays to effect opening and closing of the umbrella, and divergent cut outs at ends of the outer tube's longitudinal slots with which the runner's diametric pins co-act to effect locking of the umbrella in the open or closed state by a slight turn of said tube in reverse directions respectively.

15 In testimony whereof I affix my signature the 10th day of March, 1931, at Philadelphia, Pennsylvania.
